UNITED STATES PATENT OFFICE

VERN K. BOYNTON, OF MILWAUKEE, WISCONSIN, ASSIGNOR TO PITTSBURGH PLATE
GLASS COMPANY, A CORPORATION OF PENNSYLVANIA

GRINDING MACHINE

Application filed December 11, 1930. Serial No. 501,583.

The invention relates to a machine for grinding paint, printers' ink, chocolate and the like, and involves an improvement in the type of machine shown in the patent to S. 5 Bramley-Moore No. 1,692,884. In apparatus of this type, a fixed cylinder is employed in which is mounted a rotating arm provided with grinding elements in the form of spring pressed bars which engage the interior roughened surface of the cylinder. The object of the present invention is to increase the capacity and efficiency of the machine. Briefly stated this object is accomplished by the addition of agitators 10 mounted to move with the arm. These agitators prevent the formation of dead pockets in the corners of the cylinder and scrape the end of the cylinder free from material which would otherwise collect thereon. 15 This improvement permits a stiffer paste to be ground, reduces the power required to operate the machine, and increases its capacity or output. One embodiment of the invention is shown in the accompanying 20 drawings, wherein:

Figure 1 is a longitudinal section through a machine equipped with the improvement particularly designed for the grinding of paint. And Fig. 2 is an end elevation.

Referring to the drawings, 1 and 2 are standards or legs, upon which are supported the casing or cylinder 3 and the casting 4 which acts as a support for the driving mechanism and as a closure for the left hand 25 end of the cylinder. The other end of the cylinder is closed by the header 5 provided with the discharge outlet 6. The discharge outlet is closed by a gate 7 having a handle 8, such gate being secured in position by a 30 bar 9 provided with a clamping screw 10. The bar 9 is secured to the header by means of the stud bolts 11. An inlet 12 is provided at the left hand end of the cylinder, such inlet being closed during the operation of 35 the machine by the plate 13. A cooling chamber 14 is provided in the wall of the cylinder having the connections 15 and 16 for providing a circulation of water.

Carried in the bearing 17 at the end of 40 the casing is a hollow shaft 18 driven from

the shaft 19 by the pinion 20 and spur gear 21, the shaft 19 being driven from a motor which is not shown. The shaft 18 has keyed to its inner end the arm 22, such arm being held against endwise movement on the shaft 55 by the nut 23 fitting in a recess in the arm. The arm 22 has a slot 24 in its end in which is slidably mounted the lug 25 on the member 26. The member 26 is provided with leaf springs 27 which carry the bars 28 engaging the roughened inner surface of the casing, the construction here following that of the patent heretofore referred to. The member 25 is adjusted radially with respect to the casing by means of the rod 28 and the cone end 29 of the rod 30, a ball 31 being interposed between such end 29 of the rod and shaft as illustrated. The left hand end of the rod 30 is swivelled to the hub 32 which latter has a screw engagement 60 with the sleeve member 34. The hub 32 is provided with a hand wheel 34 for rotating it and giving the rod 30 and its cone end an adjustment in and out to regulate the pressure of the grinding rods 28 on the 65 surface of the casing. The casting 4 acts as a casing for the gears 20 and 21, the outer side of the cavity being closed by a cover which is bolted in position and carries the sleeve member 34 rigidly secured thereto. A suitable ball bearing 35 is provided for taking the end thrust of the shaft 18 and other ball bearings 36 and 37 swivel the end of the rod 30 with respect to the plate 38 clamped to the end of the hub by 70 the cap 39.

Bolted to the hub of the arm 22 so that it rotates therewith and with the shaft 18 is the hub 40, such hub being concentric with the shaft and being provided with four agitator blades 41, 42, 43 and 44 arranged in staggered relation, as shown in Fig. 1, with the blade 44 in close proximity to the end of the casing so that it acts as a scraper therefor. A scraper for the other end of 75 the casing is provided in the form of the blade 45 secured at its inner end to the hub of the arm 22 by means of the bolts 46.

In operation the casing is partially filled with a mixture of the material to be ground 80

and liquid through the opening 12, after which the motor driving the shaft 19 is started, thus causing the arm 22 to rotate carrying the grinding elements over the roughened surface of the casing, the material to be ground passing between such surface and the grinding elements. After the operation is completed, the gate 7 is removed allowing the mixture to flow through the outlet opening 6. I have found that the use of agitating and scraping blades 41, 42, 43, 44 adds greatly to the capacity and efficiency of the machine. As applied to the grinding of paint, the output of the machine is increased over 30 per cent and the power required to drive the machine with the increased capacity is reduced as compared with that required to drive it without the agitators. The use of the agitators permits the grinding of a stiffer paste than could be ground without them, thus increasing the amount of material ground at one time and constituting a contributing factor to the increased output of the machine. The efficiency of the agitators is believed to be due to the fact that they constantly throw the material outward against the grinding face of the casing, thus keeping the grinding elements supplied with the amount of material necessary to give the best results, and prevent the formation of dead pockets in which large masses of the material would otherwise collect and remain for considerable periods before becoming loosened and passing between the grinding surfaces of the machine.

What I claim is:

1. In combination in a grinding machine, a casing or drum having a grinding surface therein, a bearing at one end of the casing concentric therewith, a shaft carried by said bearing projecting into the casing and terminating intermediate the ends of the casing, means for driving the shaft, an arm carried by the inner end of the shaft, closure walls at the ends of the casing, a grinding element carried by the arm and engaging the grinding surface of the casing, and an agitating member carried by the end of the shaft, the axes thereof being arranged in alinement, such agitator including a blade which is transverse to the axis of rotation of the arm and lies adjacent the end of the casing and acts as a scraper for the closure wall remote from said bearing.
2. In combination in a grinding machine, a casing or drum having a grinding surface therein, a bearing at one end of the casing concentric therewith, a shaft carried by said bearing projecting into the casing and terminating intermediate the ends of the casing, means for driving the shaft, an arm carried by the inner end of the shaft, closure walls at the ends of the casing, a grinding element carried by the arm and engaging the grinding surface of the casing, a hub sup-

ported in alinement with the end of the shaft and mounted to turn therewith, and a plurality of laterally projecting agitating blades carried by the hub, one of which lies closely adjacent to the closure wall of the casing remote from said bearing and acts as a scraper therefor.

3. In combination in a grinding machine, a casing or drum having a grinding surface therein, a bearing at one end of the casing concentric therewith, a shaft carried by said bearing projecting into the casing and terminating intermediate the ends of the casing, means for driving the shaft, an arm carried by the inner end of the shaft, closure walls at the ends of the casing, a grinding element carried by the arm and engaging the grinding surface of the casing, a hub supported in alinement with the end of the shaft and mounted to turn therewith, and a plurality of laterally projecting agitating blades carried by the hub and arranged in staggered relation longitudinally of the hub with one of such blades closely adjacent the end of the closure wall of the casing remote from said bearing so that said blade acts as a scraper for such wall.

In testimony whereof, I have hereunto subscribed my name this 3rd day of December, 1930.

VERN K. BOYNTON.
